SHADE ROLLER

Filed Aug. 25, 1931

REISSUED

UNITED STATES PATENT OFFICE

FRED J. BURNS, OF SAGINAW, MICHIGAN, ASSIGNOR TO THE COLUMBIA MILLS, OF SAGINAW, MICHIGAN, A CORPORATION OF NEW YORK

SHADE ROLLER

Application filed August 25, 1931. Serial No. 559,227.

This invention relates to shade roller construction, and particularly to the winding mechanism thereof.

- One object of the invention is to provide 5 a simple and substantial winding mechanism, made up of a minimum number of parts, which will not get out of order; which will be cheap to manufacture, and which can be readily installed and assembled. 10 Another object is to provide new and novel means for anchoring the outer end of the spring, so that it can be readily positioned or removed, and which when the roller is assembled, is locked in position. 15 A further object is to provide a large and rugged self centering bearing of simple construction, which will run accurate and true, and which will not become sloppy with long use. 20 A still further object is to provide a winding mechanism so constructed and assembled, that all parts remain in their true assembled working relation, regardless of 25 severe blows or jars caused by hammer blows when gudgeons are inserted, or when the roller repeatedly falls on the projecting spear.

The above and other objects will appear as the specification progresses, reference being had to the accompanying drawing in 30 which I have shown the preferred embodiment of my invention, and in which like reference numerals indicate like parts throughout the several views thereof.

- 35 In the drawing: Fig. 1 is a part sectional side view of one end of a shade roller constructed in accordance with my invention.

Fig. 2 is an end view thereof. 40 Fig. 3 is a longitudinal sectional view through the winding mechanism.

Fig. 4 is a detail end view illustrating the manner of anchoring the one end of the spring. 45

Fig. 5 is a view showing the various parts in spaced apart relation.

Fig. 6 is a detail part sectional side view of the spindle and spindle ferrule, the dotted lines showing the position of the prongs before being forced into the spindle. 50

Fig. 7 is an end view of the spindle ferrule.

Referring now to the drawing in which I have shown the preferred embodiment of my invention, the numeral 5 indicates the body of the roller which can be of any suitable material, wood being most common in use, this is centrally bored as shown at 6, and is adapted to accommodate the conventional spring and spindle, 7 and 8 respectively, the inner end of the spindle having a saw cut as shown at 9, 55 and the end of the spring is shaped to fit and seat thereon, the opposite end being formed with a loop 10 for a purpose to be later described.

A ferrule member 11 fits over the outer end 60 of the spindle, the head being reduced and projecting slightly beyond the end thereof, said head being formed with a rectangular opening 12 adapted to accommodate the end 65 of the conventional spear 13, which projects into the end of the spindle, the ferrule being provided with spaced apart legs or prongs 14 (shown in dotted lines in Fig. 7) and is adapted, when the ferrule is placed in position, to be forced into the spindle to hold the 70 ferrule tightly in place.

A spool bearing 15 is journaled on the ferrule member 11 and is formed with a reduced neck portion 16 which, when assembled, projects into a centrally disposed opening 17 provided in a spool 18 and is solidly crimped over the edge thereof forming a solid unit therewith, the inner end of said spool bearing fitting over the ferrule member 11 and is formed with spaced apart laterally projecting wings 19 for a purpose to be presently described. The outer rim of the spool is turned as shown at 20, and spaced apart ears 21 are punched from the body of the spool and project longitudinally therefrom, said ears being adapted to pierce and be embedded in the roller when the mechanism is assembled. 80

A ratchet (not shown) is mounted on the 85 spear directly adjacent the turned end of the spool bearing and the usual diametrically opposite pawls (not shown) are pivotally mounted on the spool by means of rivets 24, and are adapted to engage the ratchet in the usual manner, a hub 25 being mounted on the 90 100

spear, and is interposed between the ratchet and the shoulder 26 of said spear, said hub having a centrally disposed dished center section 27 of a size to receive the head of the 5 spear. A ferrule 28 fits over the end of the roller in the usual manner, the inner end being crimped to engage the wood as shown.

In practice the spool 18 is first formed to shape and the pawls 23 are mounted thereon, 10 the spool bearing 15 is then secured to the spool forming a unit therewith, I then take the spear and assemble the hub, ratchet, spool, and spindle ferrule thereon, and then force the end of the spear into the spindle, 15 swedging the spear in the ferrule. The spring 7 is then placed in position, the one end being anchored in the saw cut 9, the opposite looped end being threaded behind the wings 19, and the loop 10 will then be locked 20 behind the ears 21, and as the winding unit is mounted in the bore of the roller, these ears together with the looped end of the spring will pierce the wood and lock the end of the 25 spring securely in position. To detach, it is merely necessary to remove the roller, bend the end of the spring to clear the ears, and it can be easily unwound from the bearing.

I wish to direct particular attention to the 30 fact that the general assembly absolutely eliminates the possibility of the mechanism becoming sloppy so that the pawls do not engage at all times; there can be no endwise movement of the ratchet without a corresponding movement of the spool on which 35 the pawls are mounted; the mechanism operates smoothly and easily, is evenly balanced, and will wear for an indefinite length of time.

From the foregoing description it will be 40 obvious that I have perfected a very simple, substantial, and economical winding mechanism for shade rollers.

What I claim is:

1. A shade roller comprising a body, a 45 spindle extending thereinto, a spool mounted on said spindle and secured to said body, and a spring anchored to one end of the spindle, the opposite end of said spring engaging said spool and being embedded and anchored in the end of the roller body when the roller is 50 assembled.

2. A shade roller comprising a body, a 55 spindle extending into said body, a spool rotatably mounted thereon, a spool bearing secured to the spool, a spring mounted on the spindle and anchored to one end thereof, the opposite end being threaded on the spool bearing, and embedded and anchored in the end of the roller body when the roller is 60 assembled.

3. A shade roller comprising a body, a 65 spindle extending thereinto, a spool mounted on the spindle, a spool bearing rigidly secured thereto and having wings projecting laterally therefrom, a spring mounted on the spindle, one end being anchored there-

to, the opposite end being threaded behind 70 said wings, and means on the spool for preventing the unwinding of the threaded end of said spring during the assembling of the roller.

4. A shade roller comprising a body, a 75 spindle mounted therein and provided with a ferrule on one end thereof, a spool having a spool bearing rigidly secured thereto and mounted on said spindle, laterally projecting wings on said bearings, a spring mounted on the spindle and anchored to one end thereof, the opposite end being looped and threaded behind 80 said wings, and means on the spool for anchoring the threaded end of the spring as the roller is being assembled.

5. A shade roller comprising a body, a 85 spindle mounted therein, a ferrule on the end of the spindle, a spool, a spool bearing secured thereto and formed with laterally projecting wings, a spring mounted on the spindle and anchored to one end thereof, the opposite end being looped and threaded behind 90 the wings of the spool bearing, and ears on the spool for engaging the looped end of the spring and piercing the body of the roller when said roller is assembled.

6. A shade roller comprising a body, a 95 spindle mounted therein, a ferrule secured to the end of the spindle, a spear mounted in 100 said spindle, a ratchet mounted thereon, a spool, a spool bearing rigidly secured thereto and formed with laterally projecting wings, a spring mounted on the spindle and secured to one end thereof, the opposite end being looped and threaded behind 105 said wings, and ears on the spool for anchoring the looped threaded end of the spring.

7. A shade roller comprising a body, a 110 spindle mounted therein, a spool having a spool bearing rigidly secured thereto, a spring anchored to one end of the spindle, the opposite end being looped and threaded behind the wings, longitudinally projecting 115 ears on the spool for engaging the looped end of said spring, and adapted when the roller is assembled to pierce the wood and force the loop against the body of the spool.

8. A shade roller comprising a body, a 120 spindle mounted therein, a spear mounted in the spindle, a ratchet, a spool mounted thereon and having a bearing rigidly secured thereto and formed with laterally projecting wings, a spring mounted on the spindle and anchored to one end thereof, the opposite end being looped and threaded behind the bearing wings, and longitudinally extending ears on the spool adapted to engage the looped 125 end of the spring to prevent the unwinding thereof.

9. The combination with a roller of a 130 spindle extending thereinto, a spool mounted on said spindle, a spring anchored to one end of the spindle, the opposite end being looped and detachably engaging the spool,

said end being adapted to pierce the end of the roller when the mechanism is assembled.

10. The combination with a roller of a spindle mounted therein, a spool mounted on said spindle and formed with spaced apart ears, a spring anchored to one end of the spindle, the opposite end being looped and detachably engaging the spool, said ears and loop being adapted to pierce the end of the

10 roller when the mechanism is assembled.

11. The combination with a roller, of a spindle extending thereinto, a spool journaled on the end of said spindle and provided with laterally projecting ears, a spring anchored to one end of said spindle, the opposite end being threaded behind said ears and anchored to said spool.

12. The combination with a roller of a spindle extending thereinto, a ferrule secured on the end of the spindle and formed with a shouldered outer end, a spool journaled on the said spindle ferrule and provided with laterally projecting ears, a spring anchored to the inner end of the spindle, the opposite end of the spring being threaded behind said ears and anchored to said spool.

13. The method of assembling a shade roller winding mechanism which consists in providing a spool, rigidly securing a spool bearing thereto to form a unit, providing a hub, ratchet and spindle, assembling the hub and spool unit on the spear, and driving the projecting end of the spear into the spindle so that the spool is free to rotate thereon.

35 14. The method of assembling a shade roller winding mechanism which consists in providing a spool having pawls mounted thereon, rigidly securing a spool bearing thereto to form a unit, providing a spindle, 40 and rigidly securing a spindle ferrule thereon, then taking a shouldered spear and assembling a hub, ratchet, and spool unit thereon in facial contact, and then driving the spear into said spindle to swedge the spear

45 in said ferrule.

In testimony whereof I hereunto affix my signature.

FRED J. BURNS.
